UNITED STATES PATENT OFFICE.

CHRISTIAN BRYNOLDT, OF PITTSBURGH, PENNSYLVANIA, ASSIGNOR TO BLAW-KNOX COMPANY, OF HOBOKEN, PENNSYLVANIA, A CORPORATION OF NEW JERSEY.

WALL FORM OR MOLD.

1,413,705.

Specification of Letters Patent. Patented Apr. 25, 1922.

Application filed May 28, 1919. Serial No. 300,485.

To all whom it may concern:

Be it known that I, CHRISTIAN BRYNOLDT, a citizen of the United States, residing at Pittsburgh, in the county of Allegheny and 5 State of Pennsylvania, have invented certain new and useful Improvements in Wall Forms or Molds, of which the following is a specification.

This invention relates to wall forms for 10 making concrete walls and the like, and has particular reference to a buttress wall mold or form.

One of the primary objects of my invention consists in the provision of an improved 15 wall form of such character that it may be utilized to form buttress walls, such for example as reservoir walls.

Another object of my invention consists in the provision of an improved wall form, 20 by means of which I am enabled to construct leaning walls, whose tops overhang their bases, or inclined walls.

Still another object of my invention consists in the provision of an improved wall 25 form of such character that it may be readily accommodated to construct walls of different slopes or inclinations or having different tapers.

My invention also contemplates the provision, in a wall form having the characteristics specified, of an improved traveler or 30 supporting structure, such traveler or supporting structure having the requisite degree of rigidity, while at the same time it is adjustable to permit of the attainment of the 35 foregoing objects.

In general, my invention is directed to the provision of what may be termed, a collapsible wall form.

40 I accomplish the foregoing, together with such other objects as may hereinafter appear, or are incident to my invention, by means of a construction which I have illustrated in preferred form in the accompanying drawings wherein:

Figure 1 is a transverse section through my improved wall form with the parts in position for the casting of the concrete, the section being taken on the line 1—1 of Fig. 50 2; Figure 2 is an irregular section taken on the line 2—2 of Figure 1; Figure 3 is a section taken on the line 3—3 of Figure 1; and Figures 4, 5 and 6 are sectional views illustrating details of my invention.

55 Referring now to the drawings, it will be seen that in general, the apparatus comprises

a traveler A, adapted to straddle the work, and to be shifted longitudinally thereof on rails 7; a front wall mold section B adapted to be supported from the traveler; a swinging framework C, also capable of support from the traveler; a rear wall mold section D and adapted to be carried by the framework C, and cooperating with the section B; buttress wall mold sections or bulkheads E, 60 also adapted to be supported from the framework C; and the lower buttress mold sections or bulkheads F. The mold sections constitute a collapsing, self supporting wall form 65 which may be used with the carrier as a unit to be shifted to cast the successive sections 70 of the wall. Or the traveler may be used with a plurality of such mold forms to carry out what may be termed a telescopic method 75 of operation in which the traveler may be utilized to set up the forms and to shift or telescope each form outside the other forms to a new casting position. The invention will first be described in connection with the unitary operation of the traveler and 80 certain of the mold sections.

The traveler A comprises a top section a, preferably in the shape of a rectangular frame composed of suitable channels 8 and connecting angles 9; and two side sections 85 or limbs b, and c, each side section being composed of a pair of trusses, suitably spaced and braced by longitudinal structural members, such as the members 10 and 11. The upper corners of the side section b are 90 braced by the angles 12, and the side section c is braced by diagonally disposed rods 13 (see Fig. 3).

The side section b, is preferably rigidly secured to the upper section of the traveler, 95 while the side section c is hinged or pivoted thereto in the manner indicated diagrammatically at 14 in Fig. 1. The purpose of hinging the side section c to the top of the carrier is to permit of adjusting the angular 100 inclination of the section so that the apparatus may be utilized in building walls of different inclinations or tapers, or in constructing center walls. To this end, I further provide both the top section and the 105 side section c, at various points, with a plurality of holes or apertures 15 adapted to receive locking pins (not shown) by means of which the side section will be supported in any adjusted position with respect to the top section. At the corners, I provide the 110 side sections with flanged wheels 16 adapted

to engage the rails 7, the flanges serving to sufficiently support the side sections against lateral displacement under ordinary conditions of service.

- 5 The wall mold section B comprises top and bottom rails or beams 17 and 18, the vertical angles 19, secured to the rails 17 and 18 in the manner shown in Figure 1, the horizontally disposed wales or nailing strips 20 adapted to carry the lagging 21. The mold section is swung or suspended from the top of the traveler by means of jacks 22 and it is supported from the side section c by jacks 23, by which arrangement 10 the wall mold section is supported adjustably but securely with reference to the side section c of the traveler, and in such manner that the mold section may be adjusted as to its inclination and to the thickness of wall 15 20 to be constructed and may be collapsed from the work after a section of the wall has been cast and has set, in order to permit the traveler to be shifted to a new position. In collapsing the mold section toward the side section c, it will be apparent that the lower end of the mold section will be cleared from the ground.

Referring now to the swinging frame C, this frame is composed of upright truss 30 members d composed of suitable structural members such as angles or the like, the trusses being spaced and braced by connecting, longitudinally disposed channels 24 and angles 25, or similar structural members. The wall mold section D is composed of lagging 26 suitably secured to nailing strips carried by the frame C. The frame C is swingingly mounted from the top section of the traveler by means of jacks 27 35 which have pivotal connection both with the frame itself and with the top section of the traveler. The frame C, with its wall mold section D, is supported and braced in a manner to be hereinafter described.

40 As hereinbefore indicated, the buttress forms or bulkheads, constituting a part of my apparatus, are made in two sections, a lower section F and an upper section E. The lower sections F are each comprised of 45 longitudinal beams 28; the nailing strips or wales 29; and the lagging 30. In setting up the lower buttress forms F, the pairs of forms may be connected at their outer ends by the detachably mounted spacing and 50 bracing channels 31 (see Figure 1) or otherwise braced. At the front the pairs of lower buttress forms are preferably spaced apart by the lower wall section G, composed of 55 suitably framings 32 carrying the lagging 33.

60 The upper buttress wall mold sections E each comprise a framework of structural members such as the angles 34 and the beams or wales 35 (see Figures 2 and 4) which carry the lagging 36. A pair of such buttress 65 wall sections E are carried by the frame C

in such manner that the sections may be collapsed toward one another. This is accomplished by supporting the sections from the frame C by means of pins 37 passing through slots 38 formed in the longitudinal channels 70 24 of the frame. The sections are adjusted, i. e. advanced or retracted by means of the jacks 39 located near the top of the frame C and the jack 40 which is secured to the framework of the mold sections in the manner indicated in Figure 2.

The corners formed by the buttress sections E and the wall section D are closed by lap joints of the construction illustrated in Figure 5, from inspection of which it will 80 be seen that at the forward edges the buttress sections are provided with beams or strips 41 over which are secured the angle plates 42 adapted to lap over the lagging 26 of the wall section D. The corners 85 formed at the top are also closed by a lap joint of similar construction (see Figure 6). By the provision of these joints the corners of the mold forms are closed so as to properly form the corners of the wall and buttresses, while at the same time it will be apparent that they do not interfere with the collapsing of the parts.

The operation of the parts is as follows.

The frame C, carrying the wall mold section D and the collapsible upper buttress mold sections E, is swung to the position indicated in Figure 1 and there supported by such means as the tackle mechanism 45. The wall section and the lower buttress forms F are now placed in position and properly braced, after which the frame C is supported and braced by suitable means, such for example as the horse or truss 43 and the wedges 46, or the braces 44 (see Figure 1) or both; and also by the beam 50, as will appear. The buttress sections E are braced by tightening the wedges 47 which are inserted between the upper and lower buttress sections, the gap between such sections being covered over by the plates 48 secured to the lagging 35 of the upper buttress sections (see Figure 4).

The other buttress mold sections, cooperating with those carried by the traveler to 115 form the buttresses, are now set in position as indicated by the dotted lines in Figure 3 and are secured in position by means of tie rods 49, or the like, diagrammatically indicated in the drawings. The ends of the buttress sections are preferably closed by end plates such as shown for example in Figure 3. The weight from the trusses or rather from the frame C, is transmitted to the buttress frames or sections by means of the 125 beam 50 supported from brackets secured to the frame work of the buttress sections and wedged in position by the wedges 51, as shown in Figure 2.

The section of the wall is now cast and 130

after the concrete has set, the tie rods 49 are first removed, which permits of the removal of the lower sections F of the buttress form, after which it is possible to collapse the buttress sections E, free of the concrete, by means of the turn buckles 39 and the jack 40. Frame C and together with it, the wall section D and the buttress sections E may now be shifted or swung rearward to the dotted line position of Figure 1, by means of tackle mechanism shown, or by other suitable mechanism, and the wall section B may be retracted in the manner previously described, by means of the jacks 23. The traveler may now be shifted to a new position and the parts positioned for another casting operation.

It will be seen from the foregoing that I have provided a simple apparatus whereby I am enabled to cast a sloping wall, such as are suitable for reservoirs, dams and the like; and that the apparatus may be readily adapted to build walls of different inclinations and tapers. It will also be apparent that the form may be utilized in casting center walls by the substitution of the proper form of wall sections, in which connection it is to be observed that the mold sections shown may be readily detached and others substituted therefor where necessary. Furthermore, the collapsing of the parts can be readily accomplished, and all of the parts when assembled constitute a rigid form. With regard to the collapsing of the mold form, it will be observed that the side section b of the traveler while it is open to permit of the retraction of the frame C and the buttress sections E, is nevertheless sufficiently rigid, because of the truss construction employed which is of considerable width at the top. (See particularly Figure 1.)

Referring now to the telescopic method of operation, i. e. the use of the traveler with a plurality of mold forms, the apparatus is employed as follows:

The traveler A is used as a carrying member to set up the forms, for the forms, as will appear, are self-supporting when set up and it will be obvious that the tackle mechanism and the jacks 22, 23 and 27 can be readily detached from the mold section to which they are respectively attached at one end, as a result of which the traveler may be utilized to set up any desired number of wall forms.

It will be apparent that the mold sections D, E, F and G, are self supporting when set up in the manner previously described, and the mold section B may be readily supported from the other sections by any preferred means and detachably secured in position by connecting elements, such for example as the tie-rods 60, which may be removed preparatory to collapsing the form.

When it is desired to shift any of the mold

forms, the traveler is brought into position and properly coupled to the mold section, after which the mold sections are collapsed, as before, and may be telescoped outside of the other forms which are in place and brought to a new position for setting up by moving the traveler along the wall. When the parts are operated in this manner the work can be accomplished with great expedition.

Other advantages of my invention will be readily understood by those skilled in the art, and furthermore, it will be understood that the apparatus is useful in constructing walls having projecting portions having shapes differing from the buttresses shown. The term "buttress," therefore, is employed in the specification and claims hereof in a broad sense.

I claim:

1. A wall form comprising in combination a traveler, a pair of oppositely disposed wall mold sections supported therefrom for relative lateral movement, and buttress mold sections supported from the traveler for relative collapse toward one another.

2. A wall form comprising in combination a traveler, a wall mold section supported therefrom for lateral movement, and a buttress mold section supported for collapsing movement and for lateral movement.

3. A wall form comprising in combination a traveler, and a buttress mold section supported therefrom for collapse from the buttress and for lateral movement to clear the buttress.

4. A wall form comprising in combination a traveler, a wall mold section suspended from the traveler for swinging movement away from the wall, and a buttress mold section suspended for such swinging movement and for collapse from the buttress.

5. A wall form comprising in combination a traveler, a frame suspended therefrom for swinging movement toward and away from the wall to be constructed, a wall mold section carried thereby, and a buttress mold section also carried thereby and mounted for lateral movement with respect to the buttress to be formed.

6. A wall form comprising in combination a traveler, a frame suspended therefrom for swinging movement toward and away from the wall to be constructed, a wall mold section carried thereby and a buttress mold section also carried thereby and mounted for lateral movement with respect to the buttress to be formed, together with means for removing the frame.

7. A wall form traveler including two suspended frames having means whereby the same may be adjusted as to inclination,

said frames being constructed to carry wall mold sections.

8. A wall form traveler including two suspended frames having means whereby 5 the same may be adjusted as to inclination, a wall mold section carried by each frame, at least one of said mold sections being adjustable with respect to its supporting frame.

10. 9. A wall form comprising a carrier and two oppositely disposed mold sections carried thereby, means for holding said mold sections in a position to construct a leaning wall, the top of which overhangs the 15 base, and a bulkhead constructed to cooperate with the leaning mold sections in forming a section of the wall.

10. A wall form comprising a carrier and two oppositely disposed mold sections carried thereby, and means for holding said mold sections in a position to construct a leaning wall, together with members co-operating to form buttresses.

11. A wall form comprising in combination a traveler, a wall mold section carried thereby, and a second and oppositely disposed wall mold section and a pair of buttress mold sections, suspended from the carrier to be swung clear of the buttresses, and 30 removable wall and buttress mold sections co-operating with said second wall mold section and said pair of buttress mold sections.

12. A wall form comprising in combination a traveler, a wall mold section and a 35 buttress mold section suspended therefrom to be swung clear of the buttress, and removable wall and buttress mold sections co-operating with said first mold and buttress sections.

14. A wall form comprising in combination a traveler, a pair of oppositely disposed wall mold sections carried thereby, and adapted to form a leaning wall, one of said sections including a wall section adapted 45 to be swung laterally and a wall mold section cooperating with said swinging section to complete the wall mold.

14. A buttress wall form comprising a supporting member, a wall mold section, and 50 a pair of buttress mold sections mounted for collapsing movement.

15. A wall form supporting member provided with two adjustable frames suspended at the top for swinging movement, and 55 means for supporting said frames in positions of adjustment.

16. A wall form comprising in combination a plurality of wall mold sections, co-operating buttress sections rendering the 60 form self supporting when in assembled relation, a carrier for shifting the sections, and means detachably supporting the sections from the carrier.

17. A wall mold form comprising a plurality of opposing wall mold sections collapsible away from the work whereby the form may be telescoped outside of adjacent impedimenta, said form including a shiftable supporting means for the wall mold sections arranged a material distance from the wall 70 to be formed to permit of such collapsing and telescoping.

18. A wall form for making leaning walls, the tops of which overhang the base, comprising a pair of inclined opposing wall mold sections and cooperating buttress forming portions, together with means for supporting the same for collapse from the work.

19. A wall form for making leaning walls comprising, in combination, a traveller, a 80 front wall mold section supported therefrom, and rear wall and buttress mold sections also supported by said traveller and shiftable rearward thereon to enable the traveller to be moved along the wall.

20. A wall form for making leaning walls comprising, in combination, a traveller, a front wall mold section supported therefrom, rear wall and buttress mold sections also supported by said traveller and swingable rearward to enable the traveller to be moved along the wall, and lower rear wall and buttress mold sections normally cooperating with the aforesaid rear wall and buttress mold sections, but separately removable 95 when the form is to be shifted.

21. In mold apparatus for forming concrete walls and the like, the combination of a traveler, and a mold section movably supported thereon for collapse from the work 100 and for movement with the traveler, said traveler being constructed so as to straddle the mold section and permit of such collapsing movement.

22. In mold apparatus for forming concrete walls and the like, the combination of a traveler having legs, and a mold section movably supported on the traveler for collapse from the work and movement with the traveler, said mold section being of less 110 length than the distance between the legs whereby the section may be moved therebetween substantially as described.

23. In mold apparatus for forming buttress walls and the like, the combination of a traveler having legs, and mold means movably supported thereon, the legs of the traveler coming opposite the buttresses and the mold means being of less length than the distance between the legs whereby the mold 115 means may be moved between legs clear of work for movement with the traveler.

In testimony whereof I have hereunto signed my name.

CHRISTIAN BRYNOLDT.
